UNITED STATES PATENT OFFICE

OTTO J. GROEHN, OF GROSSE POINTE PARK, MICHIGAN, ASSIGNOR TO HUDSON MOTOR CAR COMPANY, OF DETROIT, MICHIGAN, A CORPORATION OF MICHIGAN

OILING SYSTEM FOR INTERNAL-COMBUSTION ENGINES

Application filed February 25, 1929. Serial No. 342,427.

This invention relates to an oil tray and sump assembly and more particularly to means for circulating the oil in a splash lubricating system for internal combustion engines and for conveying the oil successively to a plurality of receptacles so that the oil will be splashed up evenly at all times to the several parts to be lubricated, and at the same time the excess oil splashed up will be intercepted, and progressively returned to the sump. By these means the amount of oil mist surrounding the parts of the engine may be controlled and the undesirable effects of over-lubrication of the cylinders avoided.

15 My invention has to do generally with a splash oiling system such as is disclosed in United States Letters Patent Nos. 1,241,589 and 1,256,754, granted October 2, 1917, and February 19, 1918, respectively to E. M. 20 White, and has for its object to provide improved means for conveying and controlling the oil splashed up, and for effecting an even lubrication by reducing turbulence in the sump.

25 Other objects of the invention will appear from the following description of a preferred embodiment illustrated in the accompanying drawings, it being understood, however, that the particular construction described 30 and shown has been chosen for purposes of exemplification merely, and that the invention is not to be limited otherwise than as defined by the claims hereunto appended and as required by the prior art.

35 Referring now to the drawings:

Fig. 1 is a longitudinal section through the oil tray and sump assembly.

Fig. 2 is a transverse section taken substantially on the line 2-2, Fig. 1.

40 Fig. 3 is a transverse section taken on line 3-3 of Fig. 1.

Fig. 4 is a sectional perspective view of the oil tray, showing the arrangement of the interceptors and oil conveyors.

45 Fig. 5 is a similar view of the oil sump and the splash plates mounted therein.

In Figs. 1 to 3 inclusive the letter A denotes the lower part of the crank case of an internal combustion engine, and the numerals 1 and 2 designate respectively an oil tray

and an oil sump or reservoir secured, the former above the latter, to the open bottom of said crank case to close said open bottom. C (Fig. 2) denotes the crank shaft having cranks B respectively connected with the several pistons (not shown) by connecting rods 10.

55 The oil tray 1, which is spaced vertically above the bottom of the sump 2, has a number of laterally extending depressions 3, 4, 5, 6, 7 and 8 which serve as troughs or receptacles in which the oil collects. The depressions are equal in number to the cranks B and are so positioned that the finger 9 carried on the end of each of the connecting rods 10 will splash up oil from one of the receptacles in a manner well understood in the art. Along one side of the oil tray means are provided to control the volume of the oil which is splashed up by the revolving 60 cranks and to limit the area of the oil mist which tends to form therearound. This means comprises the pairs of interceptors 11 and 12 which are situated respectively at one end of each of the receptacles. As illustrated, the interceptors 11 and 12 have spaced, curved, vertical walls, concave toward the receptacle, and are nested concentrically, one within the other, the interceptor 12 being of greater height than the interceptor 11. The 65 inner and smaller interceptor 11 has a plate or horizontal wall 11a across its top while the outer and larger interceptor 12 also has a plate or top horizontal wall 12a, but the latter is partially cut away centrally thereof 70 so that it will not prevent oil from being directed to all of the parts requiring lubrication. These interceptors are devised so that the smaller interceptor 11 will catch the bulk 75 of the oil which is splashed up at such an angle that it will not reach the parts to be lubricated. The larger interceptor 12 is designed to supplement this action and to intercept the oil carried momentarily by the finger on the crank shaft and thrown off 80 thereafter as it revolves. The interceptors together serve to prevent the formation of an oil mist (or drum) which otherwise surround the crank shaft and tends to rotate therewith. By this means it is possible to 85

effectually control the oil splashed up and to direct it only to the parts which require lubrication, thereby reducing to a minimum the undesirable effects produced by oil brought into contact with the pistons and sucked into the cylinders.

Attached to the side of the oil tray behind each of the pairs of interceptors, with the exception of the pair at the rearmost receptacle 8, oil conveyors 13 are provided. As illustrated in Fig. 4, each of the conveyors extends longitudinally of the tray substantially the width of each depression, and is closed at the front end but open at the rear end so that the oil which collects therein will be fed progressively to the rear adjoining receptacle. The rear end of each of the conveyors is extended transversely of the tray to form a wall 13a separating the adjoining depressions in order to more effectually prevent the oil from returning to the reservoir from which it was splashed up. In this manner the oil is splashed up from the receptacles, collected by the conveyors, and progressively passed rearwardly from one receptacle to another until it reaches the rearmost receptacle 8. The oil that gathers in the latter receptacle is splashed through an opening 14 in the side wall of the tray (see Figs. 3 and 4) by means of which the oil may be fed back into the oil sump 2.

The main oil reservoir or sump 2 is positioned beneath the oil tray and has at one end an opening 15, closed by a plug 16, through which the oil contained therein may be drained. The pipe 17, shown in Figs. 1 and 5, at the rear end of the sump serves to return the oil from the upper portions of the crank case above the tray. Positioned transversely across the sump directly in front of this pipe a splash plate 18 is provided and spaced somewhat further forward there is a second splash plate 19. These plates extend substantially across the full width of the sump with the exception of narrow spaces at each side thereof, one of which is indicated at S in Fig. 3, and may also be provided with notches or openings T adjacent the bottom of the sump. They are spaced apart so that the outlet 14 from the rearmost receptacle of the oil tray will empty into the oil sump therebetween and from which the oil will pass through the spaces S and openings T in an even flow to the main body of the sump. These plates are provided to prevent splashing of the oil returned to the sump from the upper portions of the crank case through the pipe 17 and from the tray as it is discharged through the outlet 14. In order to obtain an even lubrication at all times it is important that turbulence in the oil sump be reduced to a minimum, so that the oil may be pumped up therefrom at an even rate. The plates 18 and 19 perform an important service in accomplishing this result.

The oil tray fits into the upper portion of the oil sump, and both the sump and tray are provided with marginal flanges having holes therethrough to receive bolts 20 by which the tray and sump may be demountably secured together and to the edges of the open bottom of the crank case A. As shown in Figs. 1 and 2, a gasket 20 is secured between the flanges of the oil tray and oil sump. Heretofore it has been customary to permanently 70 secure the oil tray and oil sump together as by the use of rivets or solder, making it impossible to get at the interior of the sump to clean it thoroughly. Since it is very desirable to keep both the tray and sump thoroughly clean in order to obtain better lubrication and to avoid wear on the parts of the engine, the readily demountable arrangement of the oil tray and oil sump is an important 80 advantage of my invention.

Having thus described my invention, I claim:

1. In an internal combustion engine, the combination with the crank shaft and connecting rods, of an oil tray below said crank shaft having depressions therein constituting oil receptacles or troughs from which the connecting rods may splash up oil, and a pair of interceptors positioned adjacent one end of each receptacle, said interceptors being concave toward the receptacle and being nested one within the other.

2. In an internal combustion engine, the combination with the crank shaft and connecting rods, of an oil tray below said crank shaft having depressions therein constituting oil receptacles or troughs from which the connecting rods may splash up oil, and a pair of interceptors positioned adjacent one end of each receptacle, said interceptors having spaced, curved, vertical walls, concave toward the receptacle and concentrically arranged, the inner interceptor being of less height than the outer and having a closed top, and the outer interceptor having a top wall which is partially cut away centrally thereof.

3. In an internal combustion engine, the combination with the crank shaft and connecting rods, of an oil tray below said crank shaft having depressions therein constituting oil receptacles or troughs from which the connecting rods may splash up oil, and oil conveyors for causing the oil to be fed progressively through said depressions in succession, the rear end of each of said conveyors being extended transversely of the tray to form a vertical wall separating adjoining depressions.

4. In an internal combustion engine, the combination with the crank shaft and connecting rods, of an oil tray below said crank shaft having depressions therein constituting oil receptacles or troughs from which the connecting rods may splash up oil, an oil reservoir beneath said tray, means for feeding the

oil progressively through said depressions in succession, the wall of said tray having an opening through which the oil is finally discharged into said reservoir, and splash plates in said reservoir on either side of said opening.

5. In an internal combustion engine, the combination with a crank shaft and connecting rods, of an oil tray having depressions 10 from which the connecting rods may splash up oil, and a plurality of interceptors of unequal height adjacent the end of each receptacle, the said interceptors being arranged one behind the other in the order of height.
- 15 6. In an internal combustion engine, the combination with a crank shaft and connection rods, of an oil tray below said crank shaft having depressions therein constituting oil receptacles from which the connecting rods 20 may splash up oil, and oil conveyors for causing the oil to be fed progressively through said depressions in succession, said conveyors being carried by the tray and having integral end extensions disposed transversely of the 25 tray between the several troughs.

In testimony whereof I affix my signature.
OTTO J. GROEHN.
